UNITED STATES PATENT OFFICE.

CHARLES FERDINAND DE KIERZKOWSKI-STEUART, OF LONDON,
ENGLAND.

REVERSIBLE TURBINE.

SPECIFICATION forming part of Letters Patent No. 758,595, dated April 26, 1904.

Original application filed December 6, 1902, Serial No. 134,208. Divided and this application filed November 27, 1903. Serial No. 182,702. (No model.)

To all whom it may concern:

Be it known that I, CHARLES FERDINAND DE KIERZKOWSKI-STEUART, a subject of the King of Great Britain, and a resident of St. Stephens Club, Westminster, in the city of London, England, have invented certain new and useful Improvements Relating to Reversible Turbines, of which the following is a specification.

10 Turbine-wheels which are driven by a jet or jets of steam or other motive fluid are usually capable of rotation in one direction only.

The present invention, which has been described in application Serial No. 134,208, filed 15 December 6, 1902, of which the present application is a division, has reference to an arrangement by means of which a turbine-wheel may be made reversible. To this end I provide a symmetrically-constructed turbine-wheel—20 that is to say, one which can be equally-well acted on either way—and a deflecting device by which the jet or jets may be pointed in either direction.

In the accompanying drawings, Figure 1 25 shows in plan view a turbine-engine embodying my invention, the cover of the wheel-casing being removed. Fig. 2 is a section on the line A B of Fig. 1, and Fig. 3 is a sectional plan illustrating the deflecting device.

30 *s* is the wheel-casing, and *t* is the wheel mounted therein. This wheel is preferably of the construction shown in the drawings, in which case it consists of an outer cylindrical shell *w*, which may be wound round with wire 35 of high tensile strength and is mounted on the engine-driving shaft *v*. An annular frame *u*, fitting into the frame *w*, forms an annular

through channel or passage. This annular passage *u* is intersected by a large number of fine wires *x*, closely spaced. Immediately opposite the jets, where they enter the wheel-casing, are arranged deflectors *y*, which are capable of being shifted, as shown in Figs. 1, 2, and 3. The deflectors *y* are intended to guide the jets at a suitable angle into the annular wire-intersected passage of the turbine-wheel, through which the working fluid passes in a helical course to the exhaust-passage *z*, leading to a condenser or the outer air.

The movable deflectors are arranged in oppositely-inclined pairs (see Fig. 3) in a double ring 1, capable of sufficient rotary movement to bring one or other set of deflectors to act upon and divert the incoming jets in one direction or the other. Rotary movement is given to the ring 1 by means of an eccentric 2 and link 3. (See Fig. 2.)

What I claim as my invention, and desire to secure by Letters Patent, is—

In a turbine-engine the combination with a 60 deflecting device for the jet and means for moving said device to point the jet in either direction, of a reversible turbine-wheel comprising an inner and outer shell and an annular channel closely spaced with intersecting 65 wires, substantially as described.

In testimony whereof I have signed my name to this specification in the presence of two subscribing witnesses.

CHARLES FERDINAND DE
KIERZKOWSKI-STEUART.
